UNITED STATES PATENT OFFICE.

GEORGE BOOTH, OF CHICAGO, ILLINOIS, ASSIGNOR TO MIEHLE PRINTING PRESS & MFG. CO., OF CHICAGO, ILLINOIS, A CORPORATION OF ILLINOIS.

FLUID BUFFER.

Application filed November 16, 1922. Serial No. 601,421.

To all whom it may concern:

Be it known that I, GEORGE BOOTH, a citizen of the United States, residing at Chicago, in the county of Cook and State 5 of Illinois, have invented certain new and useful Improvements in Fluid Buffers, of which the following is a specification.

This invention relates to a new and improved fluid buffer and more particularly 10 to an air cushioning buffer especially adapted for use in connection with the reciprocating beds of printing presses.

Certain types of printing presses are 15 designed with beds which reciprocate moving relative to a cylinder, the latter being adapted to rotate with its surface in engagement with the bed. An impression is made upon each reciprocation of the bed and in order to operate the press at a high 20 rate of production, it is necessary that the bed reciprocate to a relatively high speed which may reach sixty reversals of movement per minute or greater.

The bed and its accompanying parts are 25 of considerable weight and reversal of its movement while operating at high speed occasions shocks to the mechanism. It is customary, therefore, to provide shock absorbing means adapted to cushion the movement of the bed. A customary means for 30 cushioning includes a cylinder and a piston working therein, the cushioning being accomplished by compression of air in the cylinder. It is essential for efficient cushioning that the cushioning effect be progressive 35 and not be so suddenly applied as in itself to cause a shock to the mechanism. In order to insure this progressive application, valve controlled ports are commonly provided 40 either in the cylinder or piston to control the flow of air from the cylinder, and consequently to control the air pressure in the cylinder. It is important also that no undue drag be imposed upon the 45 start of the reversing movement of the press and consequently the valve must be quick in opening to prevent the formation of a partial vacuum in the cylinder.

In certain types of valves heretofore used 50 in this connection, springs have been used to control the valve operation. This method of control is objectionable since the springs require rather delicate adjustment and fur-

ther do not maintain this adjustment due to fatigue and crystallization of the metal. 55

It is an object of the present invention to provide a new and improved buffer provided with swinging valve means adapted to control the flow of air to and from the compression cylinder. 60

It is a further object to provide valve means normally maintained open by force of gravity and further to provide means for adjusting and controlling the opening. 65

It is an additional object to provide a valve which may be readily modified to adapt it to differing conditions of speed and required air pressure. 70

It is also an object to provide a piston for use in such structures, the piston comprising simple and readily adjusted means for maintaining substantially fluid tight engagement with the cylinder walls. 75

Other and further objects will appear as the description proceeds. 75

In the drawings—

Figure 1 is a face view of a piston constructed according to my present invention;

Figure 2 is a rear view of the piston head; 80

Figure 3 is a section taken on line 3—3 of Figure 1;

Figure 4 is a section taken on line 4—4 of Figure 1; and

Figure 5 is a longitudinal section of the compression cylinder showing my improved piston in place therein. 85

The piston comprises the head 8 which is threaded upon the end of the piston rod 9 and locked in place thereon by the jam nut 90 10. As shown in Figure 5, this piston is fitted into the cylinder 11, the cylinder being provided with the removable cylinder head 12 secured in place by bolts 13.

The upper portion of the piston head is 95 provided with a plurality of ports 14 extending axially through the head. A raised valve face 15 surrounds the ports upon the inner face of the piston head as shown in Figures 1 and 4. A pair of spaced pivots 100 16 is secured to the inner face of the piston head by bolts 17. The valve member 18 is provided with the arms 19 engaging the pivots 16. The inner face of the upper portion of the valve member 18 is provided with 105 the contact members 20 adapted to engage

the raised valve face 15. These members 19 may be made of leather or other suitable material.

The lower portion 21 of the valve member 18 is bent at an angle upon a transverse line and makes an angle of approximately 30 degrees with the upper portion. The adjusting bolt 22 is threaded into the piston head and the head of the bolt 10 engages the lower portion 21 of the valve member to limit its inward swing. The washer 23 is shown under the head of the bolt 22 and the bolt is adjustable for the addition or removal of similar washers.

15 The piston head is provided with the circumferential shoulder 24 adapted to receive the packing ring 25 and to engage the shoulder 26 of the packing ring. This ring 25 may be formed of fibre or metal or other 20 suitable material. The flexible packing ring 27 is secured to the piston head by the clamping ring 28 and bolts 29. The packing ring 27 engages the cup-shaped face 30 of the packing ring 25.

25 Gravity acting upon the valve closure normally maintains it in the position in which it is shown in the drawing, in which position the valve closure is out of engagement with the valve face. The distance between 30 the closure and valve face and consequently the movement necessary for closing may be varied by adjusting the screw 22 and adding or removing washers or shims under the head of the screw.

35 As the piston head moves into the cylinder in the operation of the device, the air compressed in the cylinder will tend to rush out through the ports 14. This tendency will cause the formation of a partial vacuum 40 between the ports and the closure member, and this partial vacuum and the rush of air against the outer face of the closure member will swing it about its pivots to closed position and the air pressure within the 45 cylinder will maintain it closed during the latter part of the stroke. The valve will, however, open promptly upon reversal of movement of the piston, the air pressure from the outside through ports 14 and gravity 50 acting upon the lower portion 21 of the valve causing this opening movement.

The adjustment of the distance of closing by means of the screw 22 will take care of varying conditions and requirements. It 55 will be apparent, however, that the valves as made can be constructed with different characteristics by varying the angle between the upper and lower portions, by varying the relative weights of the upper and lower portions and by varying the areas exposed to air pressure.

60 The form of packing shown upon the piston head is particularly efficient in constructions of this type. The packing ring 25 is 65 preferably formed of hard fibre although it

may be formed of metal if desired. The shoulder 24 maintains it against circumferential expansion and the packing ring 27 maintains it against axial displacement. As shown, the ring normally expands so that 70 the shoulder 26 engages the shoulder 24 and the ring in this position is of slightly greater diameter than the cylinder. Upon being forced into the cylinder it consequently firmly engages the cylinder walls. The flexible 75 packing 27 also engages the walls and serves to prevent passage of air through minor clearances between the ring 25 and the cylinder and through the split in the ring 25.

While I have illustrated one form of my 80 device, I contemplate such changes and modifications to adapt it to various conditions of service as come within the scope of the appended claims.

I claim:

1. In a fluid buffer, a cylinder and a solid piston head movable therein, a port in said piston head, a swinging valve pivoted to the solid piston head adjacent the port, said valve being normally maintained in open 90 position and adapted to be closed against the piston head to close the port therein, by fluid pressure in said cylinder.

2. In a fluid buffer, a cylinder and a piston head movable therein, a swinging valve 95 pivoted adjacent said port, said valve being provided with a counterbalance, said counterbalance serving by gravity to maintain the valve at one limit of movement.

3. In a fluid buffer, a cylinder and a piston head movable therein, a port in said piston head, a swinging valve pivoted adjacent the port, said valve comprising a plate having two angularly related portions, one portion serving as a valve closure and the other 105 as a counterbalance adapted to maintain the valve normally at one limit of movement.

4. In a fluid buffer, a cylinder and a piston head movable therein, a port in said piston head, a swinging valve pivoted adjacent 110 the port and adjustable means engaging the valve and adapted to limit its opening movement.

5. In a fluid buffer, a cylinder and a piston head movable therein, a port in said piston head, a swinging valve pivoted adjacent 115 the port, said valve comprising a plate having two angularly related portions, one portion serving as a valve closure and the other as a counterbalance adapted to maintain the 120 valve normally open.

6. In a fluid buffer, a cylinder and a piston head movable therein, a port in said piston head, a swinging valve pivoted adjacent 125 the port, said valve comprising a plate having two angularly related portions, one portion serving as a valve closure and the other as a counterbalance adapted to maintain the valve normally open, and an adjustable stop adapted to engage the counterbalance por- 130

tion of the valve to limit the opening movement of the valve.

7. In a fluid buffer, a cylinder and a piston head movable therein, a port extending through the upper portion of the piston, a valve comprising a plate bent upon a transverse line and supported by pivots upon the piston head, the upper portion of the plate

serving as a valve closure and the lower portion of the plate being of a weight adapted ¹⁰ normally to swing the upper portion away from the face of the piston head to open the valve.

Signed at Chicago, Illinois, this 13 day of November, 1922.

GEORGE BOOTH.
